UNITED STATES PATENT OFFICE

2,606,063

LOADING MACHINE

John L. Clarkson and Alton B. Jackson, Nashville, Ill., assignors to Clarkson Manufacturing Company, Nashville, Ill., a corporation of Illinois

Continuation of application Serial No. 349,488, August 2, 1940. This application January 7, 1944, Serial No. 517,295

8 Claims. (Cl. 198—109)

1

This application is a continuation of application Serial No. 349,488, filed August 2, 1940, and now abandoned, as to subject matter common to the application.

This invention relates to gathering and loading machines, more particularly of the low-head-room type designed for use in coal mines for gathering coal from the face being worked and for loading the same on mine cars.

Many mines are of economic importance even if the veins are low—some of such veins are as low as thirty-six inches. Difficulties are encountered in operating while not only gathering but also while loading the material in a car under such low-head-room conditions. In some cases timbers still further reduce the head room. In many mines the veins are not level but up and down so as to require the machine to move uphill and downhill. Under such conditions, therefore, the gathering loader must not only be articulated to operate under such conditions, but must be capable of frequent adjustments and adaptation to such conditions.

One of the objects of this invention, therefore, is to provide a gathering loader which will operate in such a low vein and under the conditions described, but which will have ample power to handle a large tonnage.

Another object is to provide such a gathering loader structure which will be flexible so as to be able to gather and convey the material under the varying conditions described and from any point over a wide space, and to deliver the same to cars positioned in various ways with reference to the loading machine.

Further objects will appear from the following description taken in connection with the accompanying drawings, in which:

Figure 1 is a plan view partly in section of the forward end of a gathering and loading machine embodying this invention, the machine, as shown being of the Caterpillar type;

Figure 2 is a side elevation of Figure 1;

Figure 2a is a detail illustrating the operation of the lump-breaking device;

Figure 3 is a plan view partly in section of the rear end of the machine;

Figure 4 is a side elevation of Figure 3;

Figure 5 is an enlarged side view partly in section showing the driving connections for the forward conveyor; Figure 6 is an enlarged detail of Figure 3 with portions in section;

Figure 7 is an enlarged sectional detail of Figure 4; and

Figure 8 is a sectional detail of a part of Fig-

2

ure 7 illustrating another embodiment of the invention.

Figure 9 is an elevation somewhat diagrammatical in form, of a complete gathering and loading machine, the machine, as shown, being of the track type;

Figure 10 is a view somewhat diagrammatical in form showing the conditions encountered when the machine moves "uphill;" Figure 11 is a similar view showing a vein dipping "downhill."

Figure 12 is a view somewhat diagrammatical in form, showing various conditions under which the machine operates; and

Figure 13 is a similar view showing another condition.

Generally stated, and in accordance with an illustrative embodiment of this invention, the gathering loader comprises a locomotive carriage, which in the particular embodiment is low, for propelling the entire gathering-loader organization and power-operated means is connected for driving the various parts of the gathering and loading mechanisms. This carriage may be of any suitable type, examples of which are Caterpillar and track types. Material-gathering and conveying means is mounted on this carriage to extend forwardly at a low incline and this means is adapted to actively engage and gather coal encountered at the front end of the loader, i. e., from the floor of the vein and even from the face thereof, and convey the same upwardly and rearwardly and to deliver the material onto a loading conveyor structure. This latter extends rearwardly over, close to, and beyond the carriage to deliver the material so received at the rear thereof. The loading conveyor structure has a section which is pivoted at its front end and adjacent the rear end of the elevating conveyor to swing vertically with reference to the carriage, and has a terminal section which is pivoted at its front end adjacent the rear end of the first-named section to swing vertically with respect thereto into and out of the plane thereof and with reference to the carriage. These sections of the loading conveyor structure are so mounted, constructed and arranged, when so swung, to clear the carriage and the ceiling of a mine in which the gathering loader operates. A stationary or fixed section, forming a hopper, may be provided between the first-named section of the loading conveyor structure and the elevating conveyor. Power-operated means is provided adapted, during the operation of the loading conveyor, to swing the

first-named section of the loading conveyor structure vertically and also to swing the terminal section vertically with respect to the first-named section and with reference to the carriage. The terminal section may be swung with the first-named section and also vertically independently of the latter. The terminal section is also mounted to swing horizontally, and power-operated means may also be provided for effecting such horizontal movement. The loading conveyor structure has conveying means, such as flights, and this means may comprise a flight assembly which may extend from the front of the loading conveyor structure to the rear end of the terminal section. This flight assembly may be flexible, even universally, so as to flex laterally in accordance with the horizontal adjustments, as well as with vertical adjustments, of the movable sections of the loading conveyor structure. The material-gathering means may be swiveled on the carriage to swing horizontally as well as to swing vertically, and the fixed section may be mounted above the swivel.

Referring now to the drawings, and more particularly to Figures 1-8, the machine selected for illustration comprises a locomotive carriage, indicated generally at 1. Extending forwardly from the carriage at a low level at the ground is a long supporting bracket 2 which carries the forward conveyor structure indicated generally at 3 and including at its forward end gathering means including a pair of gathering chains 4 equipped with gathering arms or picks 5. The gathering devices are adapted to gather the material at the front of the machine from the face of the vein and after passing the same over the shoe 6, to deliver the material to an elevating conveyor 7. This elevating conveyor receives the material from the gathering means and it extends partly over the carriage to deliver it to a conveyor structure for loading.

The elevating conveyor 7 terminates at its end at 8 over the forward end of a delivery or loading conveyor, indicated generally at 10, so that the latter receives the material from the former. The conveyor structure 10 extends rearwardly over and beyond the carriage 1 and it is sectionalized. A stationary section 9 is fixed upon the bracket 2 so as to provide a hopper. A section 11 is pivoted at its front end at 12 adjoining the stationary section 9 and adjacent the elevating conveyor for vertical swinging movement with respect to the carriage and the stationary section. The terminal section 13 is jointed to the section 11 for both vertical and horizontal movements with respect thereto and with reference to the carriage, and the terminal section 13 is movable into and out of the plane of the section 11.

In Figures 1 to 8, inclusive, the machine is provided with Caterpillar treads and all of the mechanism is mounted on the carriage. In Figures 9 to 13 the carriage is of the track type provided with driving wheels 100 moving on a track 101. The structures may, however, be otherwise similar so that further detailed description is therefore unnecessary.

The forward conveyor 3 is mounted on the bracket 2 for both vertical and horizontal swinging movements in order that its front end may be moved to any position, relative to the carriage 1, so that material may be gathered from any point. In order to provide for such vertical and horizontal movement, and, at the same time, to keep the machine low enough to operate in such

a low vein as above mentioned, the following structure is provided:

The bracket 2 may be in the form of a casting and is provided with an upper portion 14 (Figure 5) and a lower portion 15. These two portions are spaced apart so as to receive upper and lower bearing members 16 and 17, respectively. These members may be secured to the bracket 2 in any suitable manner as by bolts 18 and 19, shown in Figure 5. The bearing members 16 and 17 provide respectively upper and lower swivel bearings for a swinging bracket 20. This bracket has a swivel bearing on the members 16 and 17 and on the member 17 at 22. The swinging bracket 20 may be provided with rollers 23, arranged to roll upon a rail 24 extending circularly around the forward end of the bracket 2. The swinging bracket 20 has the duty of carrying the weight of the front conveyor 3 and of providing a swinging pivot therefor. It thus provides vertically-spaced swivel bearing portions 21 and 22, together with the supporting rail 24 upon which the bracket may roll from one angular position to another. The fixed or stationary section of the loading conveyor structure is thus mounted above the swivel for the gathering and conveying structure. A head bracket 25 for the conveyor 3 is fixed upon the swinging bracket 20. The front conveyor boom 30 is pivoted upon the bracket 25 at 26 for vertical swinging movement.

In order to drive the front conveyor, the driving connections illustrated in section in Figure 5 are provided. A driving motor, not shown in the drawing, is mounted upon the carriage 1 and connected, as will now be described, to drive the conveyor 7. The same motor may also, if desired, be connected to propel the carriage 1.

The motor is connected by any suitable driving connections, not shown, to drive a vertical shaft 31, suitably journaled in the bracket 2. A gear 32 on the shaft 31 drives an idler gear 33, which in turn drives a gear 34 on a shaft 35. The shaft 35 is journaled in the bearing members 16 and 17. Accordingly, the gear 34 rotates on the same axis on which the swinging bracket 20 pivots. By this arrangement the drive is carried through the gear 34 to the conveyor 7 and the gathering devices in any position of the bracket 20. Meshing with the gear 34 is another idler gear 36, which drives a gear 37 on a vertical shaft 38 journaled in the forward end of the bracket 20. The shaft 38 carries a bevel gear 39 meshing with a corresponding gear 40 carried by a horizontal shaft 41 journaled in the bracket 25. The shaft 41 carries a sprocket 42, connected by a chain 43 to a similar sprocket 44 on the pivot shaft 26, which drives the elevating conveyor 7. This drive may be carried out by means of a sprocket 45 on the shaft 26 and a chain 46, passing over suitable guide sprockets to a sprocket 47 on a cross-shaft 48 extending across the conveyor boom 3. The shaft 48 carries at each end thereof a sprocket 49, and these sprockets are connected by chains 50 to sprockets 51 on shafts 52 which drive the gathering devices 4, 5. This drive for the gathering devices may be similar to that described in Patent No. 1,904,355, issued to John L. Clarkson on April 18, 1933. In order to elevate the boom 3 of the front conveyor, a pair of hydraulic jacks 53 is provided, one on each side of the boom 3. Each of these jacks is pivoted at 54 to an ear 55 on the bracket 20. At its forward end the jack is pivoted at 56 to a member

57 pivoted on the boom 3. A suitable hydraulic pump, circulating a pressure fluid such as oil, may be connected to supply the jacks 53. As these hydraulic connections may be of any suitable type well known in the art, they are not illustrated in the drawing. In order to swing the boom 3 laterally in its swivel bearings 21 and 22, cables 58 (Figure 5) are provided, passing in opposite directions around a curved flange 59 on the bracket 20 and lying in grooves 60 in 10 said flange, and anchored in ears 61 on said bracket 20. The other ends of these cables, after passing over suitable guide pulleys, are connected to hydraulic jacks operable to haul in on one cable while paying out the other so as to 15 swing the boom. As this mechanism is not a part of the present invention, it is not shown in complete detail in the drawing.

The gathering mechanism, illustrated at 4 and 5, may be similar to that described in the above mentioned patent. This comprises a pair of chains 4 passing over upper and lower sprockets 62 and 63, respectively, so that the gathering arms or picks 5 move in orbital paths. This movement is inward toward the middle of the conveyor at the lower end of such path, then upward along the conveyor, and then around the upper sprocket 62 to the return path. As the picks 5 move outwardly away from the elevating conveyor 1 in turning about the upper sprocket 62, their points may undergo a sudden increase in velocity; that is, as the picks move upwardly along the inner straight portion of their paths along the conveyor, they travel at a speed preferably a little slower than that of the conveyor 1. As they turn outwardly around the sprocket 62, the chain continues to travel at the same linear velocity. However, the picks extend outwardly from the chain and their tips may move at a radius equal to double or more that of the sprocket. Accordingly, during this portion of their movement the tips of the picks whip around this sprocket at a high velocity. If a pick happens to have a lump of material lodged thereagainst during its upward travel, it sometimes happens that the lump does not fall back on the conveyor 1 but is retained in the embrace of the pick until the latter moves around the sprocket 62. When this happens, there is a likelihood that the sudden increase in speed will cause the pick to throw the lump of material off the conveyor, sometimes with great force. This is often dangerous to the operator. In order to avoid this action, there is provided adjacent the path of the pick where it passes around the sprocket 62 a deflecting or breaking element 63 (Figure 2a). This may be in the form of a rib or fin, as shown in Figures 1, 2, and 2a. In the arrangement illustrated in Figures 1 and 2 it is formed as a continuation of the upper rim flange 64 of the conveyor. It is preferably shaped so as to tend to deflect material carried around by the pick 5 back onto the conveyor. As shown in Figure 2a, it is shaped so that the pick 5 may just clear the edge of the element 63 so that when a lump of material, indicated by dotted lines in Figure 2a, is carried around to this point by the pick, such lump will engage the element 63 and will either be deflected so as to fall back on the conveyor, or will be crushed or broken by the mutual action of the elements 5 and 63. This tends to avoid throwing large lumps of material off the conveyor.

The loading conveyor (Figure 2) is arranged in three sections. The front section 9 as shown,

is fixed on the bracket 2, as already pointed out, and has pivoted thereto at 12 the section 11; and the terminal section 13 is hinged to the section 11 at 13. In order to provide for both horizontal and vertical swinging movement of the section 13 (Figure 4), the structure shown in Figures 3 to 8, inclusive, is provided. The section 11 carries a bracket 65 (Figure 7) having a pivot bearing 66 adapted to receive a pivot pin 67. Swivelled on the pin 67 is a bracket 68, which has secured thereto a member 69 which extends forwardly of the pin 67 and terminates at its forward end in an arcuate edge 70 which lies flush with the floor of the section 11 adjacent a concave arcuate edge 71 on said floor. The arcs of the edges 70 and 71 are concentric with the pin 67, so that as the member 69 swivels on said pin it provides a substantially continuous floor for the conveyor. The member 69 is provided with pivot bearings 72, to which the section 13 is pivoted by means of short pivot pins 73. Thus, the pin 67 provides a swivel connection for swinging the section 13 horizontally, while the pivots 73 provide a hinged joint for swinging said after section 13 vertically.

The rear end of the section 11 is supported by a hoisting device, shown in the form of a hydraulic cylinder 74 (Figure 8). The extensible upper end of this device is pivoted at 75 to ears 76 on the lower portion of the bracket 68. The lower part 30 of the cylinder 74 is provided with trunnions 77 which rest in sockets 78 in a movable bracket 79, swivelled on a pin 80 which is concentric with the pin 67. The bracket 79 and the pin 80 are carried by a rearwardly-extending supporting bracket 81 on the carriage 1. The bracket 79, in addition to being swivelled on the pin 80, may be provided with rollers 82 adapted to run on a circular track 83 on the bracket 81. The latter bracket is provided with an arcuate opening 84, through which the lower end of the cylinder 74 extends in order to permit the swinging movement of said cylinder about the pin 80. The pivots 75 and 77 take care of variation in the position of the cylinder 74 as the same is extended to elevate the section 11, as shown in dotted lines in Figure 7. As the swivelled member 68—69 turns about the pin 67, the bracket 79, which carries the weight thereof, follows such movement by also swivelling about the pin 80.

In order to take care of the vertical swinging movement of the section 13, the bracket 68 is provided with ears 85 upon which are pivoted hydraulic cylinders 86, whose other ends are similarly pivoted at 87 to the section 13.

The lateral swinging movement of the section 13 is accomplished by means of a pair of hydraulic jacks 95 (see Figures 6 and 7), one on each side of the pivot pin 67. Each of these jacks is mounted by means of trunnions 96, engaging sockets 97 in the bracket 68 of the swivelled member. The other end of each of these jacks is pivoted at 98 to suitable ears 99 on the bracket 65. These jacks are operated in opposite directions, i. e., one is retracted while the other is extended, in order to swing the after section to one side or the other.

A suitable hydraulic pump and a suitable system of piping for the pressure fluid, together with suitable control valves for operating the several jacks in the desired manner, are provided. These have not been illustrated, however, as they may be of any suitable construction, well known in the art.

The conveyor chain which forms the moving element of the loading conveyor, comprising the sections 9, 11, and 13, may be of the single chain

type, comprising a chain 88, which is universally flexible, that is, flexible in two directions and which has mounted thereon a series of transverse flights 89, said flights being mounted at their middle points on the chain 88. In order that this movable chain may move easily around lateral curves when the section 13 is swung horizontally, the sections 11 and 13 are provided with side flanges 90 and 91, respectively. Arranged to span the swivelled member are two flexible flange sections 92, which are secured to the flanges 91 and extend forwardly so as to pass just outside of the flanges 90, as will be seen in Figure 3. Guides 93, secured to the flanges 90, hold the ends of the flexible sections 92 in place at the ends of the flanges 90 during the lateral swinging movement of the section 13. The sections 92 may be constructed of spring steel or similar resilient material, so that they will form themselves into smooth curves, as indicated in dotted lines in Figure 3 when the section 13 is swung to one side. Thus, the section 92, which is on the inside of the curve, provides a guide over which the flights 89 may slide in making the turn.

In place of the mounting of the hoisting device as shown in Figure 7, the cylinder 74 may be mounted for uniform movement on a ball-and-socket joint, as indicated at 94 in Figure 8.

The flexibility of the machine will be apparent by consideration of Figures 9 to 13, inclusive; for although the illustrations have a track-mounted gathering loader the advantageous features are also present in the Caterpillar type gathering loader.

The gathering mechanism will gather the material from the face of the vein and the coal or other material is then carried by the elevating conveyor 7 to the fixed section 9 which forms a hopper. The gathering mechanism is capable of vertical and horizontal movements, not only to adapt itself to the face of the coal but also the vertical and lateral contour of the vein followed by the track or roadway. The coal is taken from the hopper by the loading conveyor and deposited into a car such as shown at 102. It will be particularly noted that the loading conveyor is susceptible of movements vertically so that the delivery of the coal in the car can be effectuated under very low-head-room. This is accomplished by reason of the fact that the terminal section 13 is pivoted to the section 11 so as to swing vertically thereon, while the section 11 is also pivoted at its forward end. Furthermore, by mounting the terminal section 13 to swing horizontally on the section 11 the receiving car 102 may be on a side track or roadway.

The adaptability of the gathering loader to operate in a vein which dips, is shown in Figures 10 and 11, in which the condition is somewhat exaggerated although it must be kept in mind that the total over-all length of the machine is quite extensive, being in a particular design about 37½ feet long. Due to the fact that the gathering head can swing vertically and even horizontally, and that the sections 11 and 13 are pivoted as shown, the machine can accommodate itself to extreme conditions of rises and dips while still permitting efficient gathering and loading of the material.

Figure 12 further illustrates the adaptability of the machine if the ceiling of the mine entry be low, as indicated at A. The hinging of the terminal section for vertical movement on the section 11 and the hinging of the latter, will pre-

vent interference with the ceiling as would be the case if the terminal section were not hinged. This latter condition can readily be visualized by considering the terminal section simply an extension of the section 11 as shown by dotted lines. When the machine operates in so-called high coal where the ceiling may be higher as at B, it will be seen that here again the terminal section can work close to the ceiling, while if it were not hinged on the section 11 the condition of interference would be as indicated by dotted lines.

Figure 13 shows another condition encountered where there is not only a low ceiling A, but also timbers bracing the ceiling, one of which is indicated at C. The mine cars 102 are often made of such height that they will just pass under such timbers. Figure 13 shows how the terminal section can be worked over the front edge of the mine car and lowered so as to pass the timber, C, and reach to the end of the car. In this way the machine may be worked in a normal manner to fill the car, while providing ample clearance above both the sections 11 and 13 to permit the coal on the conveyor to be carried thereby without interference by contact with the ceiling or any downward projection from the ceiling, such as the timber C.

It will be seen, therefore, that this invention accomplishes its objects in providing a loading machine of this character, which may be built low enough to operate in low veins of coal, or the like, and under the varying conditions encountered but which is still flexible and capable of operating in any other situation. The front portion of the machine, including the conveyor 3 and its gathering devices, is strongly supported upon the carriage, while, at the same time, it is low in height. The arrangement of flat gears lying horizontally upon a low bracket provides for driving connections running forwardly a comparatively long distance without occupying the height that upstanding gears or bevel gears would occupy. The front conveyor is swivelled on the carriage by means of the members 16 and 17 in such a way as to be adequately supported by vertically spaced bearings. These are capable of sustaining a great weight suspended in cantilever relation to the carriage, while, at the same time, permitting the side swing of the boom 3.

The loading conveyor is solidly supported at its front end and arranged for elevation of its section at the rear end thereof. Accordingly, when operating in entries of normal height, this end may be elevated to reach any type of mine car. The arrangement, by which the after section 13 may swivel as well as swing vertically, provides for loading cars which may of necessity be placed laterally with respect to the carriage and at any relative elevation.

While the invention has been described as embodied in a unitary structure, it will be understood that individual features or sub-combinations thereof may be useful by themselves without reference to other features or the complete combination; and it is understood that the employment of such individual features or sub-combinations is contemplated by this invention when within the scope of the appended claims.

It is further understood that various changes may be made in the details of construction within the scope of the appended claims without departing from the spirit of this invention, and that the invention is not limited to the specific details shown and described.

Having thus described the invention, what is claimed is:

1. A loading machine of the character described, comprising a locomotive carriage, a sectional conveyor having one of its sections pivoted at its front end on said carriage for substantial elevating movement of the rear end thereof, and a second section carried by the movable part of said first section and jointed for horizontal and vertical swinging movement relative to and into and out of the plane of said first section, a hoisting device supported on said carriage and arranged for operation to elevate and lower the movable end of said first section, and means on said movable part for swinging said second section on said first section to different adjusted positions relative to the latter.

2. In a conveyor structure for a loading machine of the character described, a sectional conveyor having one of its sections pivoted at its front end for substantial elevating movement of the rear end thereof, a member horizontally swingably mounted on the rear part of said section, a second section carried by said member and mounted thereon for vertical swinging movement relative to and into and out of the plane of said first section, a hoisting device on said movable part arranged for operation to elevate and lower said member, and means carried by said member operable to swing said second section.

3. A loading machine of the character described, comprising, a locomotive carriage, a sectional conveyor having one of its sections pivoted at its front end on said carriage for substantial elevating movement of the rear end thereof, a member horizontally swingably mounted on the rear part of said section, a second section carried by said member and mounted thereon for vertical swinging movement relative to and into and out of the plane of said first section, a hoisting device supported on said carriage and arranged for operation to elevate and lower said member, and means carried by said member operable to swing said second section.

4. In a conveyor structure for a loading machine of the character described, a sectional conveyor having one of its sections pivoted at its front end for substantial elevating movement of the rear end, a member horizontally swingably mounted on the movable part of said section, a second section carried by said member and mounted thereon for vertical swinging movement relative to and into and out of the plane of said first section, a hoisting device arranged for operation to elevate and lower said member, a support for said hoisting device constructed and arranged to move laterally with said member, and means carried by said member operable to swing said second section.

5. In a conveyor structure for a loading machine of the character described, a supporting structure, a sectional conveyor having one of its sections pivoted at its front end on said structure for elevating movement of the rear end thereof, a member horizontally swingably mounted on the movable part of said section, a second section carried by said member and mounted thereon for vertical swinging movement relative to and into and out of the plane of said first section, a carrier swingable on said sup-

porting structure on substantially the same axis as said member, a hoisting device mounted on said carrier and connected to elevate and lower said member, and means supported by said first section operable to swing said second section on said member.

6. In a conveyor structure for a loading machine of the character described, a supporting structure, a sectional conveyor having one of its sections pivoted at its front end on said structure for elevating movement of the rear end thereof, a member horizontally swingably mounted on the movable part of said section, a second section carried by said member and mounted thereon for vertical swinging movement relative to and into and out of the plane of said first section, a hoisting device mounted on said supporting structure for lateral movement with said member and connected to elevate and lower said member, and means to swing said second section on said member.

7. In a conveyor structure for a loading machine of the character described, a sectional conveyor having one of its sections pivoted at its front end for substantial elevating movement of the rear end thereof, and a second section carried by said first section at the movable end thereof and jointed for horizontal and vertical swinging movement relative to and into and out of the plane of said first section, a hoisting device arranged for operation to elevate and lower the movable end of said first section, and means carried by said first section for swinging said other section to different adjusted positions relative to said first section at any position of the latter.

8. In a conveyor structure for a loading machine of the character described, a sectional conveyor having one of its sections pivoted at its front end for substantial elevating movement of the rear end thereof, and a second section carried by said first section at the movable end thereof and jointed for vertical and horizontal swinging movement relative to and into and out of the plane of said first section, and means for independently moving said respective sections to different adjusted positions.

JOHN L. CLARKSON.
